COOKING UTENSIL COVER OR SIMILAR ARTICLE

James F. Waters, New York, N. Y.

Application December 15, 1951, Serial No. 17,751

Term of patent 14 years

(Cl. D44—26)

To all whom it may concern:

Be it known that I, James F. Waters, a citizen of the United States, residing at 400 East 59th Street, in the city, count, and State of New York, have invented a new, original, and ornamental Design for a Cooking Utensil Cover or Similar Article, of which the following is a specification, reference being had to the accompanying drawing, forming part thereof.

Fig. 1 is a top plan view of a cooking utensil cover or similar article showing my new design; and

Fig. 2 is a side elevational view thereof.

The pan shown in dotted lines is for illustrative purposes only.

I claim:

The ornamental design for a cooking utensil cover or similar article, substantially as shown and described.

JAMES F. WATERS.
